UNITED STATES PATENT OFFICE.

FRANCIS M. YENTZER, OF OTTAWA, ILLINOIS, ASSIGNOR TO J. E. PORTER COMPANY, OF OTTAWA, ILLINOIS, A CORPORATION.

HAY-CARRIER.

SPECIFICATION forming part of Letters Patent No. 777,465, dated December 13, 1904.

Application filed February 18, 1904. Serial No. 194,183. (No model.)

To all whom it may concern:

Be it known that I, FRANCIS M. YENTZER, a citizen of the United States, residing in Ottawa, in the county of Lasalle and State of Illinois, have invented a new and useful Improvement 5 in Hay-Carriers, of which the following is a specification.

This invention relates to the construction of 10 hay-carriers and is an improvement upon previous constructions.

In my improved carrier the rope-pulley frame is swiveled to the supporting parts of the carrier and is permitted to turn horizontally to any angle desired, and the "drop-lock," as it 15 is called, is made in two parts, the upper part being adapted to engage the inclines of the releasing-stop upon the track and the lower portion being swiveled to the upper portion and acting to engage the grappling-dogs by 20 which the fork-hook is supported.

The details of the invention are fully explained in the description given below and illustrated in the accompanying drawings, in which—

25 Figure 1 is an elevation of the invention. Fig. 2 is a plan view thereof. Fig. 3 is a section on the line 3 3 of Fig. 1. Fig. 4 is a section on the line 4 4 of Fig. 1. Fig. 5 is a section similar to Fig. 4, showing the parts in 30 different positions. Fig. 6 is a section on line 6 6 of Fig. 2. Fig. 7 is a plan view of the drop-lock.

In said drawings, 10 represents the track, and 11 the releasing block or stop attached to 35 the track.

The car of the carrier is shown at 12 and is supported upon wheels 13, running on the side flanges of the track. The rope-pulley frame is shown at 14 and is supported from the car 40 by the engagement of its centrally-located outstanding circular rim 15 with the groove 16 in the circular depending portion 17 of the car. This swiveling attachment is adapted to permit the frame 14 to swing entirely around horizontally or to make any portion of a turn desired or necessary when loading or unloading. The upper part of the drop-lock is shown 45 at 18 and forms a U-shaped frame with the opening at the top. It is confined against

turning by providing the car with vertical 50 ways in which the drop-lock frame may fit loosely. These ways are formed by the interior ribs 20, cast upon the sides of the car. The frame is provided with the usual inward projections at the top of each of its limbs, 55 (shown at 21,) adapted to engage and ride upon the inclines of the releasing track-stop. In the bottom of the U-shaped frame is a circular opening in which the pivot-stud 22, attached to a swiveling block or frame 23, is entered 60 and upset. In this manner the block 23 is supported from the frame 18 with freedom, however, to turn with the frame 14, and said frame is recessed to fit said block, so that the latter cannot turn independently. The block 65 or frame 23 is preferably hollow in order to save weight, and it may be and preferably is square or other angular shape adapted to enter between the grappling-dogs and to hold them in their acting positions, the block having 70 similar opposite sides adapted to be presented to the dogs. The grappling-dogs referred to are shown at 24. They are pivoted to the frame 14, as at 25, and are provided with shoulders 26 at their upper ends adapted 75 to engage the swiveling block or frame 23. They are also provided with surfaces 27, adapted to set under and support said block or frame when they are in their open positions. At the lower ends they are provided with points 80 or hooks 29, adapted to enter the openings in sides of the fork-hook 30. The dogs are further provided with inwardly-extending tongues 31, which are joined together by a pin 85 32, secured in one of them and entering a slot 33 in the other of them. These tongues are in the path of the fork-pulley when it is raised into the frame 14, and the pulley then shifts the grappling-dogs from the position of Fig. 5 to that of Fig. 4. In the latter position the 90 block 23 has dropped by gravity between the top shoulders of the dogs and the points of the dogs have engaged the fork-pulley frame. The two halves of the frame 14 are provided with stops at 36, adapted to limit the entering 95 movement of the frame of the hook-sheave.

I claim—

The combination in a hay-carrier, of a car,

a rope-pulley frame swiveled to the car, a fork-pulley frame, grappling devices for engaging the fork-pulley frame, a drop-lock to be lifted by the releasing-stop upon the track and an angular block swiveled to the drop-lock and serving to hold the grappling devices in their acting positions, said swiveled block being

loosely fitted in a similarly-shaped recess of the rope-pulley frame and turning with the same.

FRANCIS M. YENTZER.
